COMBINED OVERCAP AND ACTUATOR FOR A PRESSURIZED CONTAINER

Robert E. Corba, Racine, Wis., assignor to
S. C. Johnson & Son, Inc., Racine, Wis.

Filed May 20, 1974, Ser. No. 471,425

Term of patent 14 years

Int. Cl. D9—07

U.S. Cl. D9—258

FIG. 1

FIG. 2

FIG. 3

FIG. 4

FIG. 5

FIG. 1 is a perspective view of a combined overcap and actuator for a pressurized container showing my new design;

FIG. 2 is a front perspective view thereof;

FIG. 3 is a right side perspective view thereof;

FIG. 4 is a rear perspective; and

FIG. 5 is a top plan view.

I claim:

The ornamental design for a combined overcap and actuator for a pressurized container, as shown.
